UNITED STATES PATENT OFFICE

2,490,081

HIGH-FREQUENCY APPARATUS

Eugene Mittelmann, Chicago, Ill.

Application July 23, 1942, Serial No. 452,102

4 Claims. (Cl. 219—13)

1

My invention relates to oscillators of the type used for medical, industrial and similar purposes, and is particularly directed to means for making the exposed parts of the apparatus safe for the operator to handle, so far as the possibility of contact with high D. C. or low frequency power supply potentials is concerned.

In the usual kind of high frequency heat treatment generator, electron tubes are used in an oscillator circuit for generating the desired high frequency power. Typical medical applications transfer this power to the patient by electrodes which are, in effect, simple elements of a condenser, with the patient constituting a part of the dielectric. Common industrial applications transfer the power by an induction coil, the object to be heat treated being placed in the field of the coil.

Persons working with the apparatus are exposed to contact with the electrodes or with the coils, as the case may be. Hence, these parts must be carefully insulated from the plate voltage as supplied to the electron tubes, since it generally is a dangerously high potential with respect to ground. It is usual to secure such insulation either by the application of intermediate coupling condensers, or by the use of secondary coils inductively coupled to the primary or tank coil, which is at plate potential. In the case of the coupling condenser, the safety limit is the breakdown voltage of the condenser dielectric; in the case of the inductively coupled coils, the limit is the spacing between coils, which determines the flashover potential. Neither of these limits, under practical conditions, gives satisfactory assurance of safety.

It is an object of this invention to provide a circuit for high frequency generators in which the output connections or electrodes are at ground potential.

A further object of my invention is to facilitate water cooling of the heating coil by providing a circuit in which the inlet and outlet connections for the cooling water can be at ground potential.

Various modes in which my invention may be utilized are illustrated in the accompanying drawings, in which

Fig. 1 is a wiring diagram of a high frequency generator with which heating electrodes of the condenser type are used;

Fig. 2 is a diagram of a similar type of generator, using an induction coil for transferring energy to the material treated;

Fig. 3 is a diagram of a portion of a circuit corresponding generally to Fig. 2, showing how I may

2

provide for water cooling of the heating coil and part of the tank coil;

Fig. 4 is a diagram of a circuit equivalent to that of Fig. 3, illustrating how the arrangement of Fig. 3 constitutes a bridge circuit; and

Fig. 5 is a modification of the circuit shown in Fig. 3.

Figs. 1 and 2 show a push-pull oscillator circuit, including electron tubes 10, a source of plate voltage 12, and a tank circuit in which the principal elements are the tank inductance or coil indicated generally as 14, and the tank condenser 16. In Fig. 1, radio frequency energy generated by the oscillator is transferred to the subject matter by electrodes 18, coupled to the tank coil by condensers 20. In Fig. 2, the energy is transferred by the heating coil 22, which may be directly connected to the tank coil 14, as shown, when my invention is employed.

One aspect of my invention consists in providing a balanced push-pull generator, symmetrically arranged so that the point at which the plate supply lead enters the tank circuit is at zero high frequency potential, or, let us say, at the average high frequency potential. I then ground this point, which is the positive plate supply terminal. The customary practice, of course, has been to ground the cathode or negative terminal. The ground connection in my circuit is indicated at 24 in the drawings.

In a circuit which is both mechanically and electrically symmetrical, this ground connection will be at the center of the tank coil 14. Grounding the tank coil in single-ended circuits would be impractical because of the very large capacity of the plate power supply equipment to ground; in the balanced push-pull oscillator, however, since the capacity of the power supply unit is always between points of zero or mid-potential as described above, the electrical conditions in the circuit would be unchanged, so far as the high frequency is concerned.

The advantages of such a system in both industrial and electro-medical applications will be readily understood. Insulation for high voltages is necessary only in the components associated with the negative terminal of the power supply. Ordinarily there are parts which do not offer any hazard to the operator in case of insulation failure. For instance, the transformers and other parts in the filament circuits of the oscillator tubes do not have to be accessible under normal working conditions.

With the positive high voltage terminal grounded, it is still advisable, in the usual case, to use

coupling condensers 20, in order to maintain so far as possible a balanced distribution of the high frequency potential. But even if the dielectric in one of these condensers should fail, thus short-circuiting the condenser and connecting one of the electrodes 18 directly to the tank coil, nothing more serious than a change in the high frequency potential distribution would result. Usually this would not be severe enough to change very much the potential of the object with which the electrode 18 might be in contact.

In heat treatment generators using an inductor coil 22, advantage may be taken of the efficiency of an autotransformer, since the output leads may be conductively coupled to taps on the tank coil as shown in Fig. 2.

In numerous heat treatment applications, the temperatures reached are so high that it becomes necessary to cool the coil 22. One way of doing this is to form the coil of a tubular conductor, and to circulate water through the coil. With circuits commonly used, however, insulation of the water supply is a serious problem and gives rise to many difficulties, both in design and maintenance. These difficulties are overcome by my invention, which makes it possible to have the inlets and outlets for the cooling water at ground potential.

Fig. 3 illustrates one practical arrangement which may be employed. As before, 14 and 16 represent the tank inductance and tank condenser, respectively, of a high frequency generator, the other parts of which are not illustrated, but may be as shown in Figs. 1 and 2, or any equivalent arrangement. Portions L_1 , L_2 and L_3 make up the total inductance of the tank coil 14, L_3 being the mid-portion, having the number of turns desired between the taps for heating coil leads. L_3 is a hollow tube coil with a water inlet 26 at its midpoint. The water inlet is grounded, i. e., it is connected to the positive terminal of the plate supply. The hollow tube is continued to form the leads 28 and 30, which serve both for electrical and water conducting connection to the induction heating coil 22. The latter also has a water connection at its midpoint, designated as 32. By any suitable means, not illustrated, water, or other cooling fluid may be circulated through the tubular coils, to keep the coil 22 at a safe temperature.

The circulating water and the connections to the water supply apparatus will not affect the electrical characteristics of the circuit, because both inlet and outlet are at ground potential. This fact is illustrated in Fig. 4, which is a diagram of the equivalent circuit of Fig. 3, laid out in the well known representation of a four-arm bridge. The branches of L_3 will be equal and the branches of L_4 will be equal, when these coils are center-tapped, as previously described. With these branches equal in impedance, points 26 and 32 will be at the same high frequency potential, and hence if one is grounded, the other will be at ground potential.

It is possible to balance the bridge arrangement, and thus to have 26 and 32 at equal potential, even when the two arms of inductances L_3 and L_4 are not equal, but when the impedance ratio of the two parts of the L_3 side of the bridge is the same as the ratio of the two parts of the L_4 side. Thus there is no insulation problem at all with regard to the cooling system.

With the cooling fluid circulating through a part of the tank coil, as in Fig. 3, it is not convenient to change the taps on the tank coil to

vary the coupling as may be desirable for maximum power transfer to the object being heated. An arrangement which is more flexible in this respect as shown in Fig. 5. The heating coil 22 is made of tubing, with a connection 32. The leads 28 and 30, however, run to another tubing coil 34, which carries the other connection, here designated as 36. The leads 28 and 30 are extended as 28a and 30a to taps on the coil 14, and these taps may be adjusted as desired for optimum impedance matching. The inductance value of the coil 34 is preferably made as large as practical with respect to that of the heating coil 22, in order to minimize its shunting effect. If a point on the tank coil is grounded as at 24, points of equal potential may be found on the coils 22 and 34. Locating the connections 32 and 36 at these points permits circulation of cooling fluid by any desired type of apparatus without any effect on the electrical conditions in the circuit.

In each case described, the power transfer leads and electrodes (or coil) will be at ground potential, so far as the plate supply voltage is concerned. These are the only parts with which the operator or user would be likely to come in contact in the ordinary use of the apparatus. Thus I have provided an arrangement which for practical purposes eliminates the hazard of electrocution always present with conventional apparatus.

Furthermore, I have substantially reduced the difficulties involved in connection with cooling an induction heating coil by entirely eliminating the necessity for insulation of the apparatus used to supply water or other cooling fluid.

As will be understood by those familiar with the electronic art, some changes may be made in the arrangements here described, by the modification of various parts, or the use of mechanical or electrical equivalents without departing from the real spirit and purpose of my invention. The specific examples given are intended as illustrative only, and not as limitative of the scope of my invention. It is my intention to cover by my claims any modifications of structural or electrical arrangement, or use of mechanical or electrical equivalents, which may be reasonably included within their scope.

50 In the claims I use the general term "power transfer means" to include condenser type electrodes, as illustrated in Fig. 1, or inductor heating coils as shown in Fig. 2, for example.

I claim:

55 1. In apparatus of the kind described, an electron tube oscillator having a tank circuit including an inductance, a portion of said inductance consisting of a tubular coil, a tubular induction heating coil, tubular leads connecting said heating coil and said first mentioned coil, a fluid connection on said first mentioned coil, means placing said fluid connection at ground potential, a fluid connection on said heating coil at a point of equal potential with said first mentioned connection, and a source of plate voltage for said oscillator, one terminal of said source being connected to said inductance.

60 2. In high frequency heating apparatus, a balanced push-pull electron tube oscillator having a tank circuit including a tubular coil, a tubular heater inductor, tubular leads connecting said coil and said inductor, a fluid connection at the electrical center of said coil, said connection being at ground potential, a fluid connection on said inductor, also at ground potential and a

source of plate voltage for said oscillator, the positive terminal of said source being connected to one of said points of ground potential.

3. A tubular heat inductor coil, a second coil constituting a source of high frequency energy for said inductor, a third coil, also tubular, connected in parallel with said inductor coil, and communicating therewith for fluid flow, leads extending from said inductor coil to taps on said second coil, a fluid inlet connection on one of 10 said tubular coils, and a fluid outlet connection on the other of said tubular coils at a point having the same high frequency potential as said inlet connection.

4. High frequency heating apparatus including a balanced push-pull electron tube oscillator having a tank circuit including an inductance, a tubular heater inductor, a second tubular coil communicating for fluid flow with said inductor, a fluid connection at the electrical center of said inductor, said connection being at ground potential, a fluid connection on said second tubular coil, also at ground potential, a tap on said inductance at ground potential, leads from said inductor to taps on said inductance, and a source 15

of plate voltage for said oscillator, the positive terminal of said source being connected to one of said points of ground potential.
